UNITED STATES PATENT OFFICE.

GEORGE H. FORSYTH, OF CHICAGO, ILLINOIS.

WINDOW CONSTRUCTION.

1,086,318.

Specification of Letters Patent.

Patented Feb. 3, 1914.

Application filed May 12, 1908. Serial No. 432,357.

To all whom it may concern:

Be it known that I, GEORGE H. FORSYTH, a citizen of the United States, residing at Chicago, in the county of Cook and State of Illinois, have invented certain new and useful Improvements in Window Construction, of which the following is a specification.

This invention relates to window constructions, certain features of the invention being applicable to windows of that class employing hollow sheet-metal sash members, and other features of improvement being applicable generally to sash members of any construction.

The general object of the invention is to produce an improved window construction wherein the sash should be automatically adjusted to snug engagement with the sash-guides.

My invention will be readily understood when considered in connection with the accompanying drawings showing practical embodiments of the several features there-
of, in which,—

Figure 1 is a fragmentary elevation of a portion of a sash and its guide, the latter being broken out to disclose features of the sash lock. Fig. 2 is a cross-sectional view on the line 2—2 of Fig. 1. Fig. 3 is a perspective elevation, with parts broken out, of one of the stiles of the sash and its coöperating guide, more particularly illustrating the relative location and coöperative action of the parts whereby a cushioning effect combined with an automatic adjustment of the sash to a snug fit in its guides is obtained. Fig. 4 is a vertical sectional view in a plane at right angles to the plane of the sash through the sash-stile and its guide, illustrating a somewhat simpler form of sash-cushioning and adjusting device, this view showing also a spring-actuated cushioning device on the sill adapted to engage the lower margin of the sash. Fig. 5 is a fragmentary horizontal section on the line 5—5 of Fig. 4, looking downwardly; Fig. 6 is a fragmentary vertical section on the line 6—6 of Fig. 5; Figs. 5 and 6 more particularly showing coöperating means on the sill and in the bottoms of the vertical sash guides for adjusting the sash automatically to a correct position and fit in its guides.

Referring first to Figs. 1, 2 and 3, 1 designates a hollow sheet metal stile, 2 the lower hollow sheet metal bar, 3 an intermediate

horizontal bar, and 4 the glass of a sash. 5 designates a transverse member of the window jamb or casing, to which is secured a sash guide 6, as is best shown in Fig. 2, taking the form of a relatively wide channel strip 6, the main portion whereof receives and guides a stile, while an inwardly projecting three-sided portion thereof constitutes a housing and guide for a sash-cushioning and adjusting mechanism herein-after described.

The three sides of the housing for the cushioning and adjusting device above referred to are identified in Fig. 2 as 6^a, 6^b and 6^c, for convenience in the further description thereof. Slidably mounted in this housing and engaging the walls 6^a and 6^b thereof is an angle strip 7, which extends approximately the full height of the guide, 75 the lower end of said angle-strip being slightly above the sill so as to permit said strip to have a limited downward yielding movement permitted by cushioning devices supporting the same, as hereinafter described. Secured to and within this angle-strip 7 near the upper and lower ends thereof are upper and lower cam-blocks 8 and 9, best shown in the perspective view Fig. 3. The upper surface of each of these cam-blocks is inclined or beveled in the direction of a line bisecting the angle of the angle-strip, thereby producing a sloping triangular-shaped surface 8^a and 9^a on the upper side of each of said blocks, each of these surfaces sloping downwardly from a point coincident with the angle to a line connecting the opposite edges of the angle, the direction of slope thus being oblique to the plane of the sash. The lower cam-block 9 rests upon the upper end of a coiled compression spring 10 (Fig. 3), the lower end of said spring resting upon a ledge or bracket 11 secured to the wall 6^c of the guide, and guided upon a central rod or stem 12 sliding through an aperture in the bracket 11 and carrying a stop-nut or head 13 on its lower end.

Secured to and embracing two sides of the stile 1 at points on the latter slightly above the relative locations of the cam-blocks 8 and 9 are upper and lower straps 14 and 15. Secured to or integral with that side of said straps which is adjacent to the three-sided housing of the guide are cam-blocks 16 and 17 designed to coöperate, respectively, with the cam-blocks 8 and 9.

These cam-blocks 16 and 17 are shaped externally to a loose sliding fit within the angle-strip 7 and the wall 6^c of the housing, and on their lower sides have oblique inclined or beveled surfaces mating and matching with the corresponding surfaces 8^a and 9^a of the blocks 8 and 9.

By reason of this construction it will be seen that the sash may be raised in its guides 10 to a height at which the lower cam-block 17 carried by the sash engages the bottom of the upper cam-block 8 carried by the angle-strip, it being understood that the normal distance between the cam-blocks 8 and 9 15 will be ample to permit the maximum required opening of the sash. When the sash is closed, the cam-blocks 16 and 17 carried by the stile of the sash strike, with their lower oblique surfaces, upon the upper oblique mating surfaces of the cam-blocks 8 and 9, with the double result that the shock of the fall of the sash is cushioned by the spring 10 (of which there will preferably be one on either side of the sash) and the 20 sash is automatically positioned widthwise and at the same time crowded toward the outer side wall of the sash-guide, thus producing a close fit with the latter and obviating the necessity of the usual weather 25 strips.

In Fig. 4 I illustrate a somewhat simpler form of mechanism designed to effect substantially the results above described without the use of the intermediate angle-strip 35 7. In this form of the device, upper and lower cam-blocks 18 and 19 are yieldingly supported on coiled compression springs 20 and 21 resting on brackets 22 and 23 secured directly to the wall of the three-sided housing of the guide, said cam-blocks being guided by stems 24 and 25 passing through apertures in the brackets 22 and 23, respectively. Secured to the adjacent side of the stile 1 of the sash as by rivets 26 are the 40 coöperating cam members 27 and 28. The coöperating cam faces of these several cam members may be inclined either simply in a direction at right angles to the sash or in an oblique direction to the plane of the sash, 45 so as to automatically adjust the sash either simply to a tight fit with the outer wall of the guides when the sash is closed, or to also automatically center the sash in its guides, as described in connection with Figs. 1, 2 50 and 3.

In both of the forms thus far described the springs 10 and 20 and 21 are the active agents not only in adjusting the sash, but also in cushioning the sash on its descent, 60 preventing possible injury and breakage in the event of a sudden fall of the sash. I also provide other means for cushioning and adjusting the sash which may be used either in association with the devices above described or independently thereof. Referring

more particularly to Figs. 2, 5 and 6, 29 designates a stop located in the bottom of each of the main guide-grooves, which stop has its upper surface formed on an incline whose obliquity is both transversely of and in the plane of the sash. This surface is shown at 29^a, said surface having a triangular form with its highest point or apex, designated *a*, located adjacent to the inner side of the base of the guide-groove, and its lowest edge, designated by *b*, lying diagonally across the guide-groove. Each lower corner of the sash is formed with a correspondingly shaped cam incline indicated at 30 in Fig. 1. By reason of this construction it will be apparent that, when the sash is in its lowered or closed position, the weight of the sash resting on the incline 29^a tends to crowd the sash both toward the outer wall of the guide and toward the vertical center of the sash, thus both adjusting the sash to a tight fit, as well as correctly positioning or centering it. The stop 29 may have its upper surface inclined simply in a direction transverse to the plane of the sash instead of oblique thereto, and the said stop may also be spring-supported, if desired, so as to produce a cushioning effect.

In coöperation with the last described feature I also employ a means for effecting 95 a snug closure at the lower margin of the sash, this means as herein shown consisting of a wedge-shaped strip or bar 31, best shown in Figs. 4 and 5, which is mounted upon the sill 32 and is slidable transversely 100 of the plane of the sash, being normally urged toward the sash by a series of coiled compression springs 33, which latter, together with the wedge strip 31, are preferably 105 slidably mounted in a hollow sill cap 34. The upper edge of the wedge strip 31 has an inclination corresponding and matching with that of the lower edge of the sash, so that as the strip is crowded beneath the sash a very snug and tight fit is insured, thus preventing access of dust, moisture, cold air and the like at that point.

While I have shown a plurality of coöperating pairs of cam devices for adjusting the sash, one pair alone may be employed within the purview of the invention, since by omitting the lower of the aligned pairs 16, 8 and 17, 9, the limitation to the height to which the sash may be raised is removed. It will also be observed that 115 where the lower cam members of each pair are independently supported, as in Fig. 4, or as in the case of the members 8 or 9, and 29, in Figs. 1, 2 and 3, the benefit of the combined action of both members may be 120 secured even where the two cam members of each pair may not come into contact and 125 action simultaneously, as would not be the case where any two of the lower cam members are rigidly connected or mounted on a 130

common rigid support, as, for instance, the cam members 8 and 9 of Figs. 1, 2 and 3. Furthermore, it will be evident that the cam-members carried by the sash, instead of those mounted in the guide, might be spring-supported, if desired, to effect substantially the same results.

It will be evident to those skilled in the art to which my improvements relate that variations and modifications in respect to the forms and relative arrangements of the parts may be made without involving any departure from the principles involved, or sacrificing any of the benefits and advantages secured; and hence I do not limit the invention to the particular mechanical forms illustrated, except to the extent clearly indicated in specific claims.

I claim:

- 20 1. The combination with a sash, and a sash-guide having a lateral extension, of a cam member carried by the sash and movable in said lateral extension of the guide, said cam member having a horizontally inclined engaging face, and a coöperating cam member mounted in said lateral extension, said cam members coöperating to adjust the sash to a close fit in its guides, substantially as described.
- 25 2. The combination with a sash, and a sash-guide having a lateral extension, of a cam member carried by the sash and movable in said lateral extension of the guide, a coöperating cam member mounted in said lateral extension, and cushioning means associated with one of said cam members, said cam members coöperating to adjust the sash to a close fit in its guides, substantially as described.
- 30 3. The combination with a sash, and a sash-guide having a lateral extension, of a cam member carried by the sash and vertically movable in said lateral extension of the guide, and a coöperating cam member mounted in said lateral extension, one of said cam members being spring-supported and said cam members coöperating to adjust the sash in its guides, substantially as described.
- 35 4. The combination with a sash, of the guide for said sash, and spring means for

bringing said sash into closer engagement with said guide when the sash is closed than when it is opened, said spring means serving to cushion the sash during its closure and comprising coöperating cam members one fixed with reference to the sash and the other having a slight cushioning movement only with reference to the guide, substantially as described.

5. The combination with a sash, of a guide for said sash, a stationary support, and a wedge member mounted on the support to yield in a downward direction, the sash having a lateral projection adapted to come into contact with said wedge member when the window is closed, substantially as described.

6. The combination with a sash, of guides for said sash, a pair of cams vertically movable within narrow limits in said sash guides, means connecting said cams, cushioning means for said cams, and a pair of coöperating cams mounted on said sash and adapted to engage the cams of said guides during the closure of said sash, substantially as described.

7. The combination with a movable sash and its guiding frame, of a spring-pressed member mounted on one of said elements to yield in a generally vertical direction and adapted to be engaged by the other element during the final closing movement of the sash, whereby to press the sash into closer engagement with its guide when closed than when open, substantially as described.

8. The combination with a movable sash and its guiding frame, of a wedge member mounted on one of said elements to yield in a generally vertical direction and adapted to be engaged by the other during the final closing movement of the sash and to exert a force opposing such movement in a direction oblique thereto, whereby to press the sash into closer engagement with its guide when closed than when open and to cushion the same during its closure, substantially as described.

GEORGE H. FORSYTH.
